UNITED STATES PATENT OFFICE.

WILLIAM K. LJUNGBAHL, OF PORTLAND, OREGON.

BEST AVAILABLE COPY APPARATUS FOR DISTILLATION.

Application filed June 13, 1923. Serial No. 645,115.

My invention relates to distillation of organic matter, and its main object is to provide an apparatus therefor which is applicable to any dry kiln for lumber whereby such volatile condensates as are driven off from wood by heat in the process of kiln drying may be recovered and saved as a commercial by-product.

In the operation of dry kilns as at present practiced the only object proposed is to dehydrate the contents of the kiln. Consequently, there is not only a loss of valuable condensates, but where kilns are operated on any considerable scale there is discharged into the atmosphere a volume of dense vapor which is objectionable about a saw mill, and to dissipate which is at all times more or less impracticable, and oftentimes impossible.

By my invention, the atmosphere is kept clear of such vapor, and that not only without expense, but also at a profit derivable from the value of by-products recovered by the employment of said invention.

In order to realize the saving of expense above indicated, the means employed must be used with a view to all possible economy in operation, and that is therefore made an important feature of my invention.

What constitutes my invention will be hereinafter described in detail and succinctly set forth in the appended claims.

In the accompanying drawings,

Figure I is a vertical section of a portion of one form of dry kiln, and showing my apparatus mainly in diagrammatical form of illustration applied thereto in operative relationship. The kiln shown in this figure is one of the so called blower type.

Figure II is a diagrammatical top plan of part of a group of kilns of the type shown in Figure I.

Figure III illustrates similarly to Figure I a detached dry kiln of the aspirator type.

Figure IV is a vertical section of one of the condensate separators of the kind preferably used throughout my apparatus for separating liquids of different specific gravities.

Referring to the numerals on the drawings, 1 indicates, in Figures I and II, a kiln of that type known as a blower kiln. It is susceptible of considerable variation as to details of structure and design, but the type is characterized by a discharge, substantially from the bottom or lower part of the kiln,

of the gaseous products of the drying process, and also of certain liquids that are mainly carried in suspension therein.

There is another type of apparatus known as the aspirator kiln that is characterized by provision of means for taking off the gaseous products of the drying process from the top of kiln, the liquids last named being precipitated, for the most part, to the floor of the kiln. That type of kiln is indicated by the numeral 2 in Figure III of the drawings.

My invention is designed to be applied to any type of kiln, and the two types above indicated are, in some one or another form of modification, believed to comprehend substantially all forms of kiln at present in use.

It is deemed unnecessary to describe or to illustrate at length any kiln construction further than to indicate that all kilns are provided with radiator pipes 3 which are, in operation, kept supplied with steam from a suitable source, not shown. Kilns of the type 1 are brought into operative communication with a common discharge duct 4, while those of the type 2 are provided with aspirator pipes 5 which are united in like manner, the members 4 and 5 being adapted, respectively, for the discharge of the gaseous vapors developed in the drying process from the application of heat to contents of the kilns.

For application to any form of kiln my invention comprises as a primal element a fan 6 which, being illustrated diagrammatically, may be of any preferred design and construction suitable for exhaust of air and vapors having condensable portions with which, during the drying process, the air is laden or commingled from the kiln or kilns with which it is placed in operative communication. The fan also is preferably a rotary one, which may be adapted, if desired, to be driven by the exhaust steam from the pipes 3, or by any other available power, and is connected with the kiln as through its duct 4 or the united aspirator pipes 5, according to the type of kiln employed. The fan discharge is made into a pipe or conduit 7 which assumes, within a water-cooled container, the form of a coil 8, said coil and its container constituting a condenser 9.

The condenser coil 8 leads through a connecting pipe 10, comprising a depressed portion or "goose-neck" 11, into the lower end

of the case of a scrubber 12, into which it empties, as through an upwardly-opening hooded discharge-terminal 15. The scrubber 12, being an instrumentality familiar in the art, may be briefly described as preferably comprising a closed oblong container or case divided transversely by a series of numerous foraminous baffling plates 16, and surmounted by a ventilator 17. A circulation of the scrubbing liquid (initially supplied, it may be, by priming but containing condensates) is maintained from bottom to top of the scrubber container through a pipe 18, the liquid being lifted by a rotary pump 19, for example. The pipe 18 terminates at its lower end within the said container in an open terminal 20 which preferably extends well-nigh to the bottom of the container and at its upper end terminates in a spray-terminal 23, superposed above the series of plates 16 upon which it makes discharge. The function of the scrubber is to separate and precipitate from the air introduced through the pipe 10 substantially all desirable condensable portions with which it is loaded, the air purified by such separation being liberated to the outside atmosphere through the ventilator 17.

The ventilator, scrubber, pipe 10, and pipe 7, constitute, in effect, one continuous conduit, of which the pipe 7 is the inlet and the ventilator the outlet. In operation of the apparatus, the scrubbing liquid should be kept cool, and to that end the pipe 18 is made to include a coil 24 that is suitably encased within a cooling chamber 25 which is furnished with a constant supply of water delivered as from a water main through a pipe 26.

The chamber 25 discharges its water near its end opposite that at which the pipe 26 enters it, through two cock-controlled pipes 27 and 28. Pipe 27 communicates with the lower end of the container of the condenser 9, which is provided with a waste pipe 30. Pipe 28, upon requisition, leads to the cooling apparatus for a still 32 hereinafter described.

According to my invention all cooling water for the entire scrubbing system enters the chamber 25 by the pipe 26 and leaves it by way of the two pipes 27 and 28 for the several uses already indicated. By this means an effective and very economical cooling of the system is obtainable. In passing through the container of the condenser 9 and the chamber 25 the water preferably runs counter-current to the flow through the coils 8 and 24 thereof, respectively, for the sake of best cooling effect upon the latter.

The apparatus already described is sufficient to effect separation of the condensates from the air with which it constantly issues in commingled volume from the kilns so long as they are operated in the usual manner,

and to that extent it in itself effects a complete utility. But a further economy may be provided in connection with said apparatus, through the utilization of that steam which is necessarily used in the operation of the kilns and which ordinarily goes to waste.

To the end last referred to, I provide the still 32 and bring it into operative connection with the radiator pipes 3 of the kiln. For the purpose just indicated, I provide a steam pressure regulator 34 through which all exhaust steam from the pipes 3 is directed, and conduct said steam through a heat-insulated pipe 35 to a water separator 36.

The separator 36, which may be of any usual or preferred kind well known in the art, is equipped with any ordinary or preferred type of automatic pressure-relief valve 37, so adjusted as to cause a maximum back pressure on the dry kiln heating system not exceeding say 20 pounds.

By the provision of means specified, steam heat necessary for the operation of the still may be effectively and economically obtained without impairment of the operative efficiency of the dry kiln. The water separator 36 communicates above its water level with a heating coil 38 within the still 32, being connected therewith through an intermediate cock-controlled pipe 40. 41 indicates a discharge outlet for the coil 38, and 42 a drainage outlet for drawing off the contents of the still retort.

The still is supplied from time to time with commingled condensates separated in the manner already specified from the gaseous discharge of the kiln. Those condensates are derived, in the main from three collectors, namely, the fan 6, the goose-neck 11, and the scrubber 12, in which, respectively, deposits of the condensates are made. In connection with kiln 2 a pipe may be provided for draining of accumulation of condensate-laden liquid in the bottom of the kiln.

The condensates from the collectors 6 and 11 may be discharged through branched pipes 43 and 44, attached to said collectors, respectively, the pipe 43 being extended for drainage of kiln 2 as last above stated. The pipe 44 discharges its contents along with those of the pipe 43 into a separator 45 of any usual or preferred construction which discharges its condensate output into a second separator 46. The number of separators may be increased to more than two, if desired, but two are usually enough. The type of separators 45 and 46, illustrated for example, may be briefly described as follows.

Each consists of a closed receptacle which is divided by a vertical transverse diaphragm 47 into two compartments which are in free communication with each other above and below the diaphragm. The func-

tion of the diaphragm is to separate the water and the condensates which are commingled when they enter the separator.

The condensates are accordingly entrapped in the first compartment and the water is thence discharged as through an overflow waste pipe 48. In the said first compartment the condensates float upon top of the water and are skimmed off into the separator 46 as through a pipe 50. The separator 46 is provided with pipes 51 and 52, corresponding to the pipes 48 and 50 of the separator 45, and its function, being precisely like that of the separator 45, is intended to supplement that of the separator last named with a view to effecting a more complete separation of condensates from the water with which they are associated.

The pipe 52 discharges into a storage tank 53 which may be one of any suitable and preferred construction adapted to hold accumulation of condensates until they are collected in sufficient quantity for distillation. The tank 53 should be of capacity sufficient to accommodate accumulation of condensates from the fan 6, the goose-neck 11, and, in case of need, the kiln, to meet the requirements of periodic operation of the still 32.

A storage tank 54, similar to the tank 53 is provided to receive accumulation of condensates from the scrubber 12, within the container of which a level-controlling pipe 55 rises approximately to the top of the pipe 10, but below the hood of its discharge terminal 15, above which the liquid level in the scrubber should not rise.

The pipe 55 leads into a separator 57, which in turn, by a pipe 58 leads into a second separator 59, which discharges through a pipe 60 into the tank 54. The separators 57 and 59 correspond in all respects to the separators 45 and 46, and are, like them, provided with waste pipes and with skimming pipes indicated by numerals 61 and 62, respectively.

The storage tanks 53 and 54 communicate, respectively, through cock-controlled pipes 63 and 64 with the still 32, and are also provided, respectively, with heating coils 65 and 66 which respectively communicate through intercommunicating cock-controlled pipes 67 and 68 with the water separator 36 below its water level, say, for example, with its pipe connection with its valve 37, as illustrated. Each of the coils 65 and 66 is provided with a waste pipe 69 and 70, respectively, for outflow of water whenever said coils are brought into requisition for heating the contents of the tanks 53 and 54 to desired liquidity.

The still 32 may be of any usual or preferred type. It is illustrated as provided with a rectifying column 71 of the usual kind which is in operative communication through a pipe 72 with a fractional con-

densing system comprising coils 73 and 74, respectively enclosed in cases 75 and 76, which, with their respective coils, constitute condensers. The coils 73 and 74 communicate one with the other by a goose-neck 77 which leads by way of a suitably bent pipe 77^a into a receiving pan 78, which in turn makes discharge through a cock-controlled pipe 79 into the retort of the still 32.

The coil 74, by a pipe 80, makes operative communication with a set of separators 81 and 82, corresponding substantially in form and function to the separators 45 and 46, for example, already described, and whose office is to take care of the volatiles of the condensates derivable from the still. The condenser cases 75 and 76 are kept cooled by water supplied by the pipe 27, and are connected by a cock-controlled pipe 83, each condenser being provided with a waste pipe 84 and 85. The pipe 85 is provided with a cock 86, by manipulation of which and of the cock of the pipe 83 the condensers of the fractional condensing system may be operated independently of each other.

In view of the foregoing specification the operation of my invention may be briefly described as follows.

In respect to any dry kiln it is necessary for the attachment of my apparatus only to provide a single outlet, such as the discharge duct 4, as shown in Figure I for example, or its equivalent represented in a common pipe connecting the aspirator pipes 5. To such an outlet the apparatus, substantially as described, is connected with the ultimate effect, in operation, of delivering a constant flow of air purified of the vapor of condensates with which it is laden when it issues from the duct 4, and which, were it discharged at once into the atmosphere, would diffuse the objectional vapor mentioned in the foregoing general statement. In the preferred complete organization of my apparatus even the vapor of steam from the radiators 3 is also condensed before liberation, by operation of the water separator 36.

The end accomplished of purifying the atmosphere about dry kilns is in itself an important one, but the recovering of the condensates in the accomplishment of it effects the saving of a commercial product, which, besides other advantages it affords, will pay a profit on the first cost of the apparatus and on the cost of its upkeep and operation.

By my method the flow of commingled air and gas is subjected to separation in passing through the condenser 9 and the scrubber, so that only air is liberated through the ventilator 17 in constant flow and without injurious restriction of the volume of gaseous discharge from the kiln. The producing of a crude first product, so obtained, is a com-

plete utility in itself, so that, if for any reason, it were deemed undesirable to carry on the distillation of that product at the place of production, it might nevertheless be collected into containers and transported to a distance to be distilled. However, the advantages of local distillation, the simplicity of the process for effecting the same, and the economy presented in the utilization 19 therein of otherwise waste steam, are obvious advantages presented by my invention in its ultimate completeness.

It is deemed proper to add that while the separation obtained through the employment 15 of the condenser 9 and the scrubber 12 is a continuous operation coincident with that of the dry kiln to which said apparatus is attached, the process of distillation is a periodic operation and may be carried out 20 at variable intervals to suit the convenience of the operator.

What I claim is:

1. In a unitary wood distillation plant, the combination with a dry kiln provided 25 with steam radiators for heating the same, of a conduit in operative communication at one end with the kiln and making discharge into the atmosphere, means within the conduit for separating and liquefying condensable portions from the gaseous flow therethrough, a still adapted to receive the 30 separated condensates, and means for heating the still operative from the exhaust steam of the radiators of the kiln and in operative communication therewith.

2. In a unitary wood distillation plant, the combination with a dry kiln provided 35 with closed steam heating means, of a conduit in operative communication with a kiln 40 at one end and making communication at

its other end into the open atmosphere, means within the conduit for condensing the condensable portions from the gas passing therethrough from the kiln, means for withdrawing the gas from the kiln through 45 said conduit and discharging it after the condensable portions are separated therefrom into the open atmosphere without returning it to the kiln, means of storage for the separated condensates communicating 50 with said conduit, a still communicating with said means of storage, a water separator communicating with said steam heating means and operative upon the exhaust steam of the kiln heating means, and a closed 55 heating chamber within the still in operative communication with the separator whereby the still may be heated by the steam discharged from the kiln.

3. In a unitary wood distillation apparatus, the combination of a dry kiln, closed steam means for heating the kiln, means for withdrawing vapors having condensable portions from the kiln and conducting them 60 without return to the kiln toward a point 65 of discharge into the outside atmosphere, means cooperative with said last mentioned means for condensing said condensable portions from the vapors before they reach the point of discharge into the outside atmosphere, a still in operative association with 70 said condensate separating means and adapted to receive the condensates therefrom, and means of communication between said still and said steam heating means for the kiln 75 whereby the kiln may receive its heat from the steam discharged from the kiln.

In testimony whereof, I have hereunto set my hand.

WILLIAM K. LJUNGDAHL.
